UNITED STATES PATENT OFFICE.

ERASTUS D. CHESEBRO, OF STONINGTON, CONNECTICUT, ASSIGNOR TO THE ATWOOD MACHINE COMPANY, OF STONINGTON, CONNECTICUT, A CORPORATION OF NEW JERSEY.

SPINDLE-RETAINING DEVICE.

1,071,297.

Specification of Letters Patent.

Patented Aug. 26, 1913.

Application filed December 8, 1910. Serial No. 596,326.

To all whom it may concern:

Be it known that I, ERASTUS D. CHESEBRO, a citizen of the United States, and resident of Stonington, in the county of New London 5 and State of Connecticut, have invented a new and useful Spindle-Retaining Device, of which the following is a specification.

My invention relates to a spindle retaining device, and more particularly to means 10 for retaining the spindle of a spinning or winding machine from unintentional displacement while removing a bobbin therefrom.

In practice, the quick removal of a bobbin 15 has frequently resulted in unseating the spindle from its step, causing delay. My present invention is directed to simple means for preventing such unseating of the spindle and consequent delay, by providing a retaining device which will hold the spindle 20 in its step whatever be the normal lift on the spindle due to the friction between the bobbin and spindle at the moment of removing the bobbin therefrom and which 25 will at the same time in no wise hinder the free rotary movement of the spindle and will admit of the ready removal of the spindle from its step when desired.

A practical embodiment of my invention 30 is represented in the accompanying drawings in which,

Figure 1 is a view in side elevation of a spindle, its whirl and step, showing the retaining device in its relation thereto. Fig. 35 2 is a top plan view of the same, showing the spindle in section and the flange at the bottom of the whirl partly broken away, and Fig. 3 is a vertical central section of the same.

40 The spindle is denoted by 1, its whirl by 2 and the spindle base by 3. The lower end of the whirl is provided with a ledge or flange 4 extending outwardly therefrom, as the preferred means for placing it under 45 the control of the retaining device. The retaining device preferably consists of a bolt or plunger 5 seated in a horizontal perforation 6 in the upwardly extending end 7 of an arm 8 branching from and formed integral with or fixed to the spindle base 3. The part 7 extends upwardly to such an ex-

tent as to bring the perforation 6 above the flange 4 on the whirl. The bolt or plunger 5 is provided with two annular grooves 9 and 10, which are adapted to receive the 55 upper arm of a spring 11 made fast to the part 7 and projecting through a slit 12 extending downwardly from the top of the part 7. When the spring arm 11 is in the groove 9, the bolt or plunger 5 will be held 60 in position with its inner end over the flange 4 so that the whirl 2 and hence the spindle 1 cannot be lifted sufficiently to unseat the spindle. In the event it is desired to remove the spindle, the spring arm 11 65 may be pressed out of the groove 9 and the bolt or plunger 5 slid outwardly until the spring arm 11 seats in the groove 10. For convenience in sliding the bolt or plunger 5 outward or inward, the adjacent walls of 70 the two grooves 9 and 10 are beveled as at 13, 14, so that a positive endwise push on the bolt or plunger will force the spring arm 11 downward and permit the bolt or plunger to slide until the spring arm is seated in the adjacent groove. The opposite 75 walls of the said grooves are, however, abrupt, so that the bolt or plunger is positively held against displacement from its seat in the perforation 6, unless the spring arm be 80 forced down and held down while the bolt is withdrawn to a point beyond the groove 10.

This simple device is a positive stop against the unintentional removal of the 85 spindle while permitting its intentional removal.

What I claim is:

1. The combination with a spindle provided with a ledge and a spindle base provided with an arm, of a spindle retaining device seated in said arm in position to slide over the said ledge, the said retaining device being provided with a groove having an abrupt side and a beveled side and a 95 spring in position to enter the groove.

2. The combination with a spindle provided with a whirl having a ledge thereon and a spindle base provided with an arm projecting outwardly and upwardly therefrom, of a spindle retaining device seated in said arm in position to slide over said 100

edge, the retaining device being provided with grooves spaced apart thereon, and a spring arranged to enter either one of said grooves to hold the retaining device in either locking or releasing position.

In testimony, that I claim the foregoing as my invention, I have signed my name in

presence of two witnesses, this 5th day of December 1910.

ERASTUS D. CHESEBRO.
